United States Patent Office

Des. 178,121

Patented June 26, 1956

178,121

STREET LIGHTING REFRACTOR

Kurt Franck and Robert G. McPhail, Newark, Ohio, assignors to Holophane Company, Inc., New York, N. Y., a corporation of Delaware

Application November 14, 1955, Serial No. 38,887

Term of patent 14 years

(Cl. D48—16)

Fig. 1.

Fig. 2.

Fig. 2

Fig. 4

Figure 1 is a side elevational view of a street lighting refractor showing our new design;

Figure 2 is an inverted plan view of the same;

Figure 3 is an end view of the same taken from the left of Figures 1 and 2; and

Figure 4 is a perspective view.

We claim:

The ornamental design for a street lighting refractor, as shown.
